UNITED STATES PATENT OFFICE.

HUGO C. RASSMANN, OF BEAVER DAM, WISCONSIN, ASSIGNOR TO F. RASSMANN MFG. CO., (INCORPORATED,) OF BEAVER DAM, WISCONSIN.

STALL CONSTRUCTION FOR ANIMALS.

1,126,566.

Specification of Letters Patent.

Patented Jan. 26, 1915.

Application filed April 1, 1914. Serial No. 828,901.

To all whom it may concern:

Be it known that I, Hugo C. RASSMANN, of Beaver Dam, in the county of Dodge and State of Wisconsin, have invented certain new and useful Improvements in Stall Construction for Animals; and I do hereby declare the following to be a full, clear, and exact description of the invention, such as will enable others skilled in the art to which it appertains to make and use the same.

This invention relates to improvements in stall construction for animals, objects of the invention being to provide simple and efficient means whereby the structure may be easily and quickly adjusted to accommodate animals of different sizes and thus avoid possibility of the droppings escaping the stall gutter.

With these and other objects in view, the invention consists in certain novel features of construction and combinations of parts as hereinafter set forth and pointed out in the claims.

In the accompanying drawings, Figure 1 is a side view, partly in section of a stall structure embodying my improvements; Fig. 2 is a face view partly broken away; Figs. 3 and 4 are enlarged detail views showing the adjusting devices on the stanchion; Fig. 5 is a view showing the manger portion and a modified form of the lower adjusting devices for the stanchion; Fig. 6 is a view taken at right angles to Fig. 5, showing the modified adjusting means, and Fig. 7 is a view in section on the line *a—a* of Fig. 5.

1 represents the base or floor of a stall and may, if desired, be of concrete. The usual curb 2 may be provided and on this curb, brackets 3 are mounted and secured thereto by means of bolts 4, the latter being anchored in the curb by a cross bar 5.

Each bracket 3 may be made in a single casting and comprises two members 6, 6, between which the lower end of one of the stall standards 7 is securely clamped by means of bolts 8. The bracket 3 is elongated in form and each of its members is made with a horizontal flange 9 formed with a plurality of pockets or recesses 10 and in the bottom of each pocket, an elongated opening 11 is made, all for a purpose which will be herein-after explained.

Side rails 12 which divide the stalls, are secured at their upper ends to the standards 7 by means of clamps 13 and the lower ends

of said rails terminate in standards 14 secured to the floor or base 1.

At the upper ends of the standards 7, elongated brackets 15 are located. Each of these brackets comprises two separate members 16—16 having seats to receive a stall standard 7 and are securely clamped to the latter by means of bolts 17. Each member 16 of each bracket 15 is provided with a lateral flange 18 formed with a plurality of pockets 19 having elongated holes 20. The vertical portion of each bracket member constitutes an abutment flange for a purpose presently explained.

A cross bar 21 is seated at its respective ends in pockets of bracket members secured respectively to two of the stall standards 7 and cross bar 21 is removably secured against vertical displacement by bolts 22 passing transversely through said cross bar and the elongated holes 20 in the pockets,—undue longitudinal movement of the bar being prevented by the abutment flanges on the bracket members. A similar cross bar 23 is seated at its ends in pockets in the members of brackets 3 at the lower ends of two of the stall standards 7 and secured against vertical displacement by bolts 24, and limited in longitudinal movement by the abutment flanges of the bracket members.

A stanchion 25 of any preferred construction is disposed between the cross bars 21 and 23 and supported by the same through the medium of suitable connecting devices such as indicated at 26 and 27.

From the construction and arrangements of parts above described, it will be readily seen that the cross bars 21 and 23 together with the stanchion 25 may be adjusted forwardly or backwardly to accommodate animals of different lengths, by merely mounting the ends of said cross bars in different pockets of the supporting brackets.

If desired, the brackets 3 at the lower ends of the stall standards and the bottom cross bar 23 may be omitted and in their stead, a single elongated bracket 28 may be anchored in the floor centrally between the stall standards and provided with a plurality of holes to receive a bolt 29, whereby the lower connecting device 27 of the stanchion may be attached at different positions on said bracket 28.

It will be understood that my improved stall structure contemplates the employment

of a plurality of stalls, and that one member of each supporting bracket (3 or 15) receives a stanchion supporting bar (21-23) for one stall and that the other member of 5 each of said brackets receives a stanchion supporting bar for the adjacent stall.

It is common practice to provide a manger 29 common to all the stalls of a series and it is very desirable that this manger shall be 10 subdivided so that portions thereof shall be segregated from other portions, and thus prevent an animal in one stall from reaching feed intended for animals in other stalls. For this purpose I provide partitions, such 15 as indicated at 30 Fig. 5, which is made to conform to the contour of the manger. Each partition 30 has secured thereto a hinge member 31, and the other member of this hinge consists of a bracket 32 clamped to 20 one of the stall standards 7. The bracket 32 is made with upper and lower parallel arms 33-34 which embrace the hinge members 31 and serve to guide the partition and also to take up any lateral strain to which 25 it may be subjected. The hinge member 31 is pivotally connected with the upper arms 33 of the bracket 32 by a hinge 35 which passes through suitable holes in said arms 33 and through an elongated slot 36 in the 30 upper portion of the hinge member 31. With such construction, the partition may be raised as shown in dotted lines in Fig. 5, and, by reason of the elongated slot 36, said partition may (when in an upright position) be permitted to drop a limited distance and rest against the intermediate por-

tion of the bracket 32,—the partition being thus held in its elevated position without the use of springs.

Having fully described my invention what 40 I claim as new and desire to secure by Letters-Patent, is:—

1. The combination with stall standards, of elongated brackets secured thereto, each bracket having a part provided with a plurality of pockets and an upwardly projecting flange at right angles to each pocket, and a stanchion-supporting bar mounted at its ends in pockets of brackets on two of said standards and having its ends adjacent to 50 the upwardly projecting flanges on the brackets.

2. The combination with stall standards, of elongated brackets secured to said standards and having vertical abutments, each bracket having a part provided with a plurality of pockets at right angles to said abutments, and each pocket having a hole therein, a stanchion-supporting bar mounted at its ends in pockets of brackets on two of said standards and between the abutments on the respective brackets, and bolts passing through said bar and through holes in the pockets of said brackets.

In testimony whereof, I have signed this 65 specification in the presence of two subscribing witnesses.

HUGO C. RASSMANN.
